E. Whitman,

Cradle.

Patented Mar 27, 1835.

Ezra Whitman Jun.

for a Machine to propel Cradles and churns.

The schedule referred to in these Letters Patent, and making part of the same, containing a description in the words of the said Ezra Whitman Jun. himself, of his improvement in a machine to propel cradles and churns —

To all, to whom these Presents shall come

Be it known, that I, Ezra Whitman Jun. of Winthrop the country of Kennebec and State of Maine, have invented a new and useful improvement in a Machine to propel Churns and also Cradles, and that the following is a full and exact description of the construction and operation of the said Machine as improved & invented by me. —

Fig. 1. (See the accompanying plate) represents the cradle as prepared for use. A the cradle or churn (B) the case enclosing the clockwork which swings them. When a cradle is to be attached to the clockwork, I make it in the usual form and attach one end firmly to the rod or verge which plays into the escapement. In the other end I fit a pinion which plays into a docket; the weight is then wound up. If this cradle or churn is made to swing back and forth as it descends.

For a churn I make an oblong or other shaped box and attach it in like manner to the clock-work, & it is made to swing or tilt and thus agitate the cream until the butter shall come. —

Fig. 2. Illustrates the combination of clock or wheel-work, by which I effect or produce the desired motions. A. the weight. B. the ratchet wheel. C. a large spur or bevel wheel which plays into the cogs of a pinion on the shaft D. is the escapement or toothed wheel upon the same shaft. D. the verge by which the cradles or churns are attached

Fig. 3. is a linear view of the same combination of wheel or
stock-work

Claims - What I specifically claim as my improvement, and
for which I request an exclusive right, is the application of the
machinery as above described.

In testimony, that the above is a true specification
of my said improvement as above described, I have hereunto
set my hand this fifth day of March in the year of our Lord
1835 -
